UNITED STATES PATENT OFFICE.

CLARENCE A. CROWDER, OF BURLINGTON, IOWA.

GASEOUS-FUEL HEATER.

1,102,478.

Specification of Letters Patent.

Patented July 7, 1914.

Application filed March 13, 1913. Serial No. 753,998.

To all whom it may concern:

Be it known that I, CLARENCE A. CROWDER, a citizen of the United States, residing at Burlington, in the county of Des Moines and State of Iowa, have invented certain new and useful Improvements in Gaseous-Fuel Heaters, of which the following is a specification.

My invention relates to improvements in gaseous fuel heaters and has particular reference to means for use in connection with the exhaust of one or more engines for heating and mixing the charge before it is exploded.

15 One object of my invention is the provision of a heater for use in connection with any character of combustion engine which can be operated practically and efficiently with crude oil, oil distillate, alcohol, or other 20 inexpensive liquids capable of such use, whereby a great saving in expense is insured by the use of my improvement.

Another object of my invention is the provision of a heater capable of use in connection with one or a series of cylinders of an engine and which, while insuring the highest degree of efficiency will be of the simplest and cheapest possible construction and be very durable, thus combining the 30 requisites to produce a thoroughly efficient improvement.

With these ends in view, my invention consists of a heater of the character and for the purpose stated embodying novel features of construction and combination of parts, substantially as disclosed herein.

Figure 1 represents a side elevation of a heater constructed in accordance with and embodying my invention. Fig. 2 represents 40 a central vertical sectional view of the heater, and Fig. 3 represents a vertical transverse sectional view of the invention.

In general configuration, my heater is of 45 rectangular shape, and is of such construction that it may be cast or formed in a single piece, and comprises the outer casing or shell A, provided at one end with an opening B, and upon its upper and lower sides with a pair of openings C and D, 50 which series of openings serve as connections for the exhaust pipe or pipes of a series of cylinders of an internal combustion engine, or for a single cylinder, and when only a single cylinder is accommodated, the 55 openings C and D may be closed by suitable caps or covers, which are not shown, and all

of these openings lead to the hot-air surrounding space or chamber E, and this chamber at one end is provided with an outlet F, which permits the escape of the products of combustion to the atmosphere.

The heater is connected to the manifold of a gas engine at N' or O', according to the piping of the manifold.

The inlet of the exhaust can be connected at openings F, G, or V, which are in the outside jacket of the heater. The carbureter may be connected at P or Q, and the action of the heater is as follows: The stroke of the piston of the internal combustion engine, causes a suction of air and fuel from the carbureter at P, thence through the chambers L, M, N. The exhaust from the engine flowing through the chamber E, heats said chambers L, M, N, causing a rapid production of vapor from heavy oils. The flue N is also provided with an opening N', with which is connected the water supply pipe R leading from the valve casing S, having the inlet pipe T, and in said valve casing is a float U, controlling a valve which maintains a constant level in casing S. At the top of the casing S, an air inlet pipe S' is provided, whereby the air which is drawn therethrough by the suction of the engine passes over the water in the casing and carries with it water vapor. This permits only the proper amount of vapor to be drawn in by the suction of the engine to form the proper mixture with the fuel for driving the engine. The purpose of the opening V may also be to permit the introduction of a blow torch or other heating agent for the purpose of initially heating the fuel chambers or flues to vaporize the fuel that passes through these flues to the engine. The torch is used only when starting the engine and requires about three minutes to perform its office and these openings, when not in use are closed by suitable caps or covers, as will be readily understood.

It will be understood that when my heater is used with only one cylinder the inlets at the top and bottom of the casing are closed by means of plugs or caps, as indicated by dotted lines in Fig. 3, and it will also be understood that the torch openings, when not in use, are closed, and also that my heater is properly connected when in use by well known means which I have not deemed necessary to show, the important and vital points to my invention residing in the fact

that my heater is compact in size and capable of accommodating a number of cylinders, and also that the exhaust is used to heat the fuel and that the proper mixture of water with the heated fuel is insured to produce a most efficient charge and at the same time prevent improper explosion of the charge, and that generally in every particular the heater will prove thoroughly efficient and practical:

I claim:

The heater herein described, consisting of a horizontal casing adapted to be connected between the carburetor and manifold of an internal combustion engine, a plurality of inlets to any one of which the carburetor is adapted to be attached, and a plurality of outlets to any of which the manifold is adapted to be connected, horizontal partition walls forming a circuitous passage for

the mixture from the carburetor, an outer shell provided with a series of openings to any two of which inlets and outlets for the exhaust gases may be respectively connected, a valve casing outside the heater, 25 a pipe leading therefrom to the circuitous passage, a float valve in said valve casing adapted to admit water to the latter, whereby water vapor is introduced into said passage, the side wall of said heater having 30 openings adapted to permit the application of a torch for the preliminary heating of said heater.

In testimony whereof I affix my signature in presence of two witnesses.

CLARENCE A. CROWDER
